UNITED STATES PATENT OFFICE.

BENJAMIN W. JACOBS, OF LANCASTER, OHIO.

DESIGN FOR A GLASS DISH.

No. 38,440.

Specification for Design.

Patented Feb. 5, 1907.

Application filed January 9, 1907. Serial No. 351,571. Term of patent 7 years.

To all whom it may concern:

Be it known that I, BENJAMIN W. JACOBS, a citizen of the United States, residing at Lancaster, in the county of Fairfield and State of Ohio, have invented a new, original, and ornamental Design for Glass Dishes, of which the following is a specification, reference being had to the accompanying drawing, forming part thereof.

The figure is a side elevation of a glass dish, showing my new design.

I claim—

The ornamental design for a glass dish, as shown.

BENJAMIN W. JACOBS.
